US0D1078621S

(12) **United States Design Patent** (10) **Patent No.:** **US D1,078,621 S**
(45) **Date of Patent:** **** Jun. 10, 2025**

(54) **CHARGING CASE**

(71) Applicant: **Starkey Laboratories, Inc.**, Eden Prairie, MN (US)

(72) Inventors: **Joshua Braband**, Minneapolis, MN (US); **James M. Helberg**, Farmington, MN (US); **Dayne N. Tanner**, Salt Lake City, UT (US); **Jack A. Marple**, Salt Lake City, UT (US)

(73) Assignee: **Starkey Laboratories, Inc.**, Eden Prairie, MN (US)

(**) Term: **15 Years**

(21) Appl. No.: **29/882,077**

(22) Filed: **Jan. 10, 2023**

(51) **LOC (15) Cl.** **13-02**

(52) **U.S. Cl.**

USPC **D13/108**

(57) **CLAIM**

The ornamental design for a charging case, as shown and described.

DESCRIPTION

FIG. 1 is a front right perspective view of a charging case in accordance with an embodiment of the claimed design; FIG. 2 is a front elevation view of the design of FIG. 1; FIG. 3 is a left side elevation view of the design of FIG. 1; FIG. 4 is a right side elevation view of the design of FIG. 1; and,

FIG. 5 is a top plan view of the design of FIG. 1. The dash-dash broken lines in the Figures are for the purpose of illustrating portions of the charging case that form no part of the claimed design. The dot-dash broken lines in the Figures represent the boundaries of the claimed design that form no part of the claimed design.

1 Claim, 5 Drawing Sheets
